UNITED STATES PATENT OFFICE.

ISRAEL MILLER, OF PAWTUCKET, RHODE ISLAND, ASSIGNOR OF ONE-HALF TO JAMES H. TAYLOR, OF PAWTUCKET, RHODE ISLAND.

MASSAGE DEVICE.

1,173,838.

Specification of Letters Patent. Patented Feb. 29, 1916.

Application filed June 23, 1915. Serial No. 35,833.

To all whom it may concern:

Be it known that I, ISRAEL MILLER, a citizen of the United States, residing at Pawtucket, in the county of Providence and State 5 of Rhode Island, have invented new and useful Improvements in Massage Devices, of which the following is a specification.

My invention relates to massage devices, and more particularly to an applicator.

10 The primary object of my invention is to provide a rotating applicator which is adapted to impart a vibratory movement to the skin.

Another object of my invention is to provide 15 an applicator having such a surface that it may be used for massaging by the old method of rubbing when not rotated, and which may be used as a vibrator when in motion.

20 Another object of my invention is the provision of a rotating applicator that is capable of imparting a number of different vibratory movements to the skin.

A further object of my invention is to provide 25 a massage device that is simple, neat and efficient in construction and which may be manufactured at a nominal cost.

This invention consists of the novel features and parts, and combinations of the 30 same, which will be more fully described hereinafter and pointed out in the claims.

A practical embodiment of the invention is represented in the accompanying drawings forming a part of this specification, in 35 which similar characters of reference indicate corresponding parts in all the views, and in which:

Figure 1 is a side elevation of my device showing it applied to a suitable motor; Fig. 40 2 is an enlarged view of my applicator; Fig. 3 is a transverse section taken on the line 3—3 of Fig. 1; Fig. 4 is a longitudinal section taken on the line 4—4 of Fig. 2; Fig. 5 is a transverse section taken on the line 5—5 45 of Fig. 2; Fig. 6 is an end view of Fig. 2; and Fig. 7 is a detail view of one of the knobs.

Referring to the drawings, 1 designates a handle having a disk 2 formed on the upper 50 end thereof. Suitably secured to the disk 2 is a motor 3.

4 designates a plate having the opposite ends thereof bolted to the frame of the

motor. This plate 4 is provided with an enlarged intermediate portion which is adapted to rigidly support a bearing rod 5 upon which the applicator 6 is journaled. The plate 4 is so attached to the motor as to have its intermediate portion lying in a plane with the axle 7 of the motor. The axle 7 is 60 adapted to pass through the plate 4 and project beyond the surface of the plate. Rigidly secured to the projected portion of the shaft is a small gear 8.

The applicator is indicated at 6 and comprises an annular body 9 which is provided with a longitudinally disposed central bore 9', one end of the applicator body being provided with an annular rib 10 to which is suitably secured an internally toothed gear 11. The bearing rod 5, as previously stated, is permanently secured to the enlarged portion of the plate 4 and extends laterally therefrom as shown in the drawings. The applicator being rotatably mounted upon the bearing rod 5 and the bearing rod being disposed on a plane above that of the motor shaft, the internally toothed gear mounted upon the applicator will mesh with the small gear 8 when in its proper position. The 75 body of the applicator is formed with an annular groove 12 adjacent one end thereof, and fixed in the side walls of the groove 12 are shafts 13, extending longitudinally of the body and spaced apart and carrying 80 rollers 14, respectively. The opposite end of the body of the applicator is provided with an annular series of circular openings 15 arranged concentrically of the axis of the body and which receive bearing pins 16. 85 Rotatably mounted upon the bearing pins 16 are an annular series of knobs 17. The bearing rod 5 is threaded at its outer end to receive a nut 18 which locks the applicator 7 upon the bearing. When the applicator 6 is 90 locked upon the bearing rod 5 just described and the motor is energized, motion will be transmitted from the shaft of the motor and through the gearing to the applicator, which will impart a rotary motion thereto. 100

It will be seen from the foregoing construction that when electric current is caused to flow through the motor 3 the gear 8, meshing with the internally toothed gear 11, will cause the applicator to rotate upon the bearing rod 5. It is, of course, understood that

owing to the spaced relation of the rollers 14 and knobs 17 a vibratory motion will be imparted to the skin when brought into contact therewith. Owing to the fact that the rollers 5 and knobs are rotatably mounted within the body, friction between the aforesaid and the skin will be eliminated. The knobs 17 being rotatably mounted within the body and disposed on the end of the body will permit the 10 user to massage the skin when the applicator is not rotated.

From the foregoing description, taken in connection with the accompanying drawing, the advantages of the construction and of 15 the method of operation will be readily apparent to those skilled in the art to which the invention appertains, and while I have herein described the principle of operation of the invention, together with the device 20 which I now consider to be the best embodiment thereof, I desire to have it understood that the device shown is merely illustrative, and that such changes may be made when desired as are within the scope of the claims 25 appended hereto.

Copies of this patent may be obtained for five cents each, by addressing the "Commissioner of Patents, Washington, D. C."

Having thus described my invention, I claim:

1. In an applicator, an annular body, knobs rotatably mounted in one end of said body, rollers rotatably mounted in the side 30 of said body, and means for rotating said body.
2. In an applicator, an annular body provided with an annular groove, an annular series of spaced rollers rotatably mounted in 35 said groove, an annular series of knobs rotatably mounted in one end of said body, and means for rotating said body.
3. In an applicator, a body, rollers rotatably mounted therein and longitudinally disposed thereon, knobs rotatably mounted within said body and longitudinally disposed thereon, and means for rotating said body.

In testimony whereof I affix my signature 45 in presence of two witnesses.

ISRAEL MILLER.
